[57] CLAIM

The ornamental design for a belt pack, as shown and described.

DESCRIPTION

FIG. 1 is a front elevational view of a belt pack, showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a front elevational view in open position.
The broken line showing of environment in FIGS. 1
and 7 is for illustrative purposes only and forms no part
of the claimed design.

FIG. 1

FIG. 2
